INVENTOR:

John Egan.

UNITED STATES PATENT OFFICE.

JOHN EGAN, OF MILWAUKEE, WISCONSIN.

IMPROVEMENT IN PNEUMATIC ACTIONS FOR PIPE-ORGANS.

Specification forming part of Letters Patent No. 179,902, dated July 18, 1876; application filed January 6, 1876.

To all whom it may concern:

Be it known that I, JOHN EGAN, of Milwaukee, in the county of Milwaukee, in the State of Wisconsin, have invented certain Improvements in Pneumatic Action on Sound-Boards of Organs, of which the following is a specification:

The object of my invention is to give quicker and more certain action in the pneumatic action on sound-boards of organs; and consists in the construction of parts, as herein-after described, to give a particularly-quick movement of the valves, by which the operator may have complete control of the organ.

Figure 1 is a sectional view of my invention.

A is the outside case; B, the lower or outside valve; C, the middle valve; D, rod with which the valve C is held open; E, spring which closes the valve B; F, the bellows; G, upper valve, which opens to let air to the pipe I; H, spring attached to and keeps the upper valve closed; I, organ-pipe; K, rod attached to valve B, which, with a pedal or manual key, operates the valves B and C; L, air-chamber; M, air-passage to the bellows; O, air-passage to the air-chamber; P, a stop on rod D, which holds valve C open; Q, rod with

which the projection R on the bellows opens the valve G, when the bellows collapses.

Operation: The organ is put in position to play by air being forced into air-chamber L through opening O, and when a pipe is wanted to sound a pedal or other key attached to rod K is touched, and valve B is opened, and as it is opened the pressure on stop P is removed, and valve C closes by the pressure of air on same, and the pressure of the air on the bellows collapses it, and the projection R on the end of the bellows opens valve G and lets the air pass to the pipe, and the organ sounds, and when the valve C is closed again the air passes through passage M to the inside of the bellows, and it is ready for action again, the bellows being inflated by the action of spring H, which closes the valve G at the same time.

I claim—

In a pneumatic action for organs, the valves B, C, and G, the spring E, and bellows F, combined and arranged to operate substantially as and for the purpose described.

JOHN EGAN.
